United States Patent Office.

JOHN B. SCHENCK, OF MATTEAWAN, NEW YORK.

Letters Patent No. 99,008, dated January 18, 1870.

IMPROVEMENT IN PLANING-MACHINES.

The Schedule referred to in these Letters Patent and making part of the same.

To all whom it may concern:

I, JOHN B. SCHENCK, of Matteawan, in the county of Dutchess, in the State of New York, have invented certain Improvements in Machines for Planing Wood, of which the following is a specification.

The object of this invention is, first, to provide, in a wood-planing machine, a better and more efficient means of equalizing the pressure of the feed-rollers upon the wood that passes through the machine to be operated upon; second, to provide a ready means of knowing the distance that the side or edge-cutters are apart, and thus know the exact width of the lumber being planed; and third, the providing of a more efficient means of pressing and keeping the lumber against the guide while the lumber is passing through the machine; and

It consists in the especial construction and arrangement of the devices which operate to produce the desired result in the different parts of the machine, in the operation of planing lumber.

In the accompanying drawings—

Figure 1 is a side elevation;

Figure 2 is a top or plan view;

Figure 3 is a longitudinal section of fig. 2 on line A' A';

Figure 4 is a cross-section on line y y of fig. 3;

Figure 5 is an end view of the end next the operator; and

Figure 6 is a cross-section, on line x x of fig. 3, of the machine, and in which—

A represents the frame of the machine, constructed to receive the necessary feed and delivery-rollers, cutter-cylinder or cylinders, and all the operating parts of the machine;

B B B are the usual feed-rollers; and

B' B' are the delivery-rollers, all placed in the usual manner with relation to the frame and cutters.

C is the surface-planing cylinder, having the cutters thereto attached, and journaled in the frame A, and revolved in the usual manner.

D and D' are the upright cutters, which dress the edge of the lumber in passing through the machine.

These cutters are attached to and revolve in journal-boxes in the movable nuts d and d', which have arms e and e' extending down and between transverse guides e" e", that serve to hold them from any longitudinal movement with relation to the machine, while they are free to move laterally, in either direction, upon guide-rod f, as may be desired, in order to give the necessary width between the cutters D and D'.

To nut d' and nut a' is attached the longitudinal guide a, against which the lumber is closely pressed in passing through the machine.

This guide a is movable laterally with relation to

the machine, so that it can be adjusted to any width of lumber within the capacity of the machine to plane.

When this guide a is moved either toward or from the centre of the width of the machine, edge-cutter D' on nut d' moves with it, by means of revolving the longitudinal screw-shaft E' on the right-hand side of the machine, or by revolving lateral screw-shafts F" F", as the lateral shafts F" F" are connected to and revolve with longitudinal shaft E' by gear-wheels or pinions upon each shaft, which gear-wheels have inclined teeth in their peripheries, so that they work together, although their shafts are at right angles to each other.

The lateral screw-shafts F" F" pass through the right-hand side of frame A, and work into and through nuts d' and a', and have proper bearings in the left-hand side of frame A.

Nut a' is attached to the guide a by means of a neck that extends upward through and works in slot a" in a cross-tie of frame A, said slot acting as a guide to direct it in a lateral direction when the screw-shaft F" is revolved.

Upon the left-hand side of the machine is placed a horizontal longitudinal screw-shaft E, upon which are gear-wheels or pinions, working into pinions or gear-wheels on lateral screw-shafts F F', and having the same inclined teeth upon their peripheries, as before described as being on screw-shafts E' and F" F'.

The lateral screw F passes through the left-hand side of frame A, and works into and goes through nut c', the neck of which extends up through a slot in the cross-tie of frame A, and as the screw-shaft F is revolved, it moves nut c" in a lateral direction, or across the width of the machine.

At the same time, and with the revolution of lateral screw-shaft F, the lateral screw-shaft F' is revolved by being connected together by shaft E and the gear-wheels, and which, in like manner, goes through the left-hand side of frame A, and into and through nut d, carrying edge-cutter D, and into a proper bearing in the right-hand side of frame A, and as the said screw-shaft F' is revolved, it forces edge-cutter D to move laterally, either toward or from the centre of the width of the machine, according to the direction that shaft E or shafts F and F' are revolved.

By the construction and arrangement of these two sets of screw-shafts with their connecting gear-wheels, as above described, both edge-cutters can be adjusted to edge a board or plank of the width of the extent of the capacity of the machine to dress, or they can be brought into close contact, near the centre of the width of the machine, and thus edge a very narrow piece of lumber.

The longitudinal screw-shafts E and E' have screw-

threads cut upon them, for a considerable distance, from near the end toward the operator.

Said shafts are properly and securely journaled in fixed boxes G G, which hold the shafts from any longitudinal reciprocation or movement, but allow them to freely revolve in said boxes G G.

These screw-shafts E and E' screw into and pass through the sliding split-nuts g g.

The nuts g g slide in elongated slots or openings in each side of the frame A, and in the direction given by the revolution of the longitudinal shafts E and E', and are attached, on the inside of frame A, to sliding levers or connecting-bars I, at g', as seen in fig. 3.

The sliding levers I are attached to sliding nuts I', which freely slide upon guide-pieces J.

H H are two weighted levers, one placed at each side of the machine, and inside of the frame A, and have adjusting sliding weights h h, that can slide upon and be fixed to the said levers H H.

The levers are sustained and have a fulcrum in stirrups H', which extend upward and inside of frame A, to the yokes H" H", to which they are firmly attached.

The yokes H" H" are constructed so that each end thereof bears upon the freely perpendicular-sliding boxes in the sides of frame A.

The boxes hold the journals of the upper feeding-rollers B B, and are made to slide, to accommodate the different thickness of stuff that may be planed in the machine, and so that said feed-rollers may rise or fall, to accommodate such difference, or any irregularity of thickness the lumber may have.

Weighted levers H H, at or near their forward ends, always rest against the under side of the sliding nuts I' I' at whatever point they may be at on guides J J.

By this arrangement and construction of devices, it will be seen, that whenever the longitudinal screw-shaft E', at the right-hand side of the machine, is revolved in the right-hand direction, it will bring the sliding split-nut g toward the operator who feeds the machine, and with it the sliding lever I and nut I', and shorten the distance between the fulcrum of weighted lever H and its bearing-point on sliding nut I'.

By reversing the direction of the revolution of longitudinal screw-shaft E', the direction of movement of the sliding nut I' will be reversed, by which means the distance between the fulcrum of weighted lever H and its bearing on sliding nut I' is increased.

As the said shaft E' is revolved, through its connections with lateral screw-shafts F' F", they are also revolved, and such revolution changes the position of the guide a and edge-cutter D' toward or from the centre of the width of the machine, as desired.

On the left-hand side of the machine is a longitudinal screw-shaft, E, constructed and arranged to operate in the same manner as shaft E' above described, and operates another sliding lever I, and nut I', on guide J of the left-hand side of machine, and for the same end, which is to change the length of fulcrum of the weighted lever H; and at the same time as the said shaft E is revolved, it moves the edge-cutter D, either toward or from the centre of the width of the machine, and nut c" is also reciprocated in the same manner as cutter D.

With this especial arrangement and construction of devices above described, the pressure is equalized upon the top feed-rollers, in such a manner that the lumber, in passing through between the feed-rollers, will be pressed by the top feed-rollers equally hard at all points of its width, no matter at what point of the width of the machine the lumber may be passing, and bearing against the guide a, as the difference in the distance between the fulcrum of the weighted lever and the sliding nut on the right-hand side of the machine, and the weighted lever and its sliding nut on the left-hand side of the machine, will cause a differ-

ence of pressure, through the yoke H", upon the two ends of the feed-rollers, for, as the guide a is forced toward the middle of the width of the machine, and consequently the side of the lumber next the guide will be nearer the centre of the rollers, the nut I' is moved further away from the fulcrum of lever H in stirrup H', and the weight on lever H cannot act with the same force as it would if the said lever H had a shorter purchase, and hence, the pressure is less on the right-hand end of the feed-rollers, while the edge-cutter D has, in order to admit the width of stuff, been also moved toward the left-hand side of the machine, and therewith the sliding nut I' has been moved toward the fulcrum of weighted lever H, and hence the weight operates through the stirrup and yoke upon the left-hand end of the rollers with a proportionate increase of force, and in the same ratio as the force has been decreased on the right-hand end of the said rollers.

Transversely across the machine, and at a proper height above the platform, is a guide-plate, b, firmly secured, at both ends, to the sides of frame A.

Sliding upon this guide-plate is the slide b', which has a graduated scale upon the side next the operator, and is connected, by an arm, to longitudinal guide a, so that as guide a is moved toward or from the centre of the width of the machine, the slide b' also moves upon guide-plate b, and corresponds with the movement of guide a.

Upon the slide-plate b' is a sliding index, c. This index c is moved by means of a curved arm, c', which is attached at its upper end to index c, and at the other end to sliding nut c", so that as nut c" and edge-cutter D are moved laterally, the index-plate will have a corresponding movement upon the sliding plate b'.

By this arrangement of devices, connected with the graduated scale on the sliding plate b', the width of the lumber wrought in the machine can be correctly known and determined, and can be adjusted by turning either the right or left-hand longitudinal screw-shaft, and can be adjusted to any desired width of stuff being wrought.

l" is a presser-lever, to press the lumber firmly against the guide a, and is pivoted to sliding nut c", and moves laterally with nut c" and edge-cutter D.

To the outer end of said presser-lever l" is pivoted a connecting-bar, l', and bar l' is pivoted to the end of lever l, which has a handle upon the end opposite to where it is pivoted to the connecting-bar l', and in a convenient position for the operator to take hold of the handle, and pulling the same toward himself, will keep the lumber firmly against the longitudinal guide a.

I am aware that revolving screw-shafts have been used to move and adjust edge-cutters and the longitudinal guides in planing-machines. I am also aware that attempts have been made to adjust the presser-feed-rollers, to equalize the pressure of such rollers; and that index-plates have been used for determining the width of the stuff being dressed; and also that presser-levers have been used for holding the lumber firmly against the guide; but the constructions and arrangements which have been used for these several purposes are not what I have described as my invention, and I lay no claim to such as have been heretofore described and used.

Having fully described my invention, its use, and application,

What I claim as new, and desire to secure by Letters Patent, is—

1. The combination of the transverse screw-shafts F F' F", and their sliding nuts a' c' d' d", edge-cutters D D', and guide a, with the longitudinal screw-shafts E E', sliding nuts g, connecting-bars I, sliding nuts I', slides J, weighted lever H, stirrups H', yokes H", and presser feed-rollers B B, when constructed

and arranged in the manner and for the purpose described.

2. The combination of the revolving screw-shafts and their transverse sliding nuts and edge-cutters above described, with the guide *a*, slide-bar *b*, graduated sliding scale *b'*, and sliding index *c*, when arranged in the manner and for the purpose described.

3. The compound presser-lever, composed of the presser-foot *l'*, connecting-bar *l*, and pivoted lever-handle *l*, and connected to sliding nut *c'*, in the manner and for the purpose described.

4. An improved planing-machine, in which is provided a means of regulating the amount of pressure upon the ends of the presser-rollers, by changing the fulcrum of the weighted lever, in the manner substantially as described.
